UNITED STATES PATENT OFFICE.

ARCHIBALD STURROCK, OF WINNIPEG, MANITOBA, CANADA, ASSIGNOR TO THE
CANADIAN PACIFIC RAILWAY COMPANY.

VENTILATING AND DEFLECTING OF AIR THROUGH RAILWAY CARS.

Application filed June 14, 1926, Serial No. 115,843, and in Canada May 28, 1926.

Heretofore it has not been possible to obtain proper ventilation in railway cars and particularly in so called refrigerator express cars for carrying perishables because the air intakes were not provided with means for efficiently deflecting the air to the space beneath the floor rack to cause it to be effectively diffused throughout the car. The object of my invention is to diffuse fresh air upwardly throughout the interior of the car from the floor.

To this end my invention consists in providing railway cars and more particularly cars for carrying perishables with a ventilator whereby air is induced into the top of the car by the forward movement thereof and practically the entire body of air taken in is precipitated downwardly near the forward end of the car and deflected into a flat air distributing member extending substantially parallel and comparatively close to the floor of the car. More specifically stated the invention consists of ventilators at both sides of the opposite ends of the car and constructed and arranged to act alternately as intakes of fresh air and outlets for the used air, according to the direction in which the car is travelling. With each of these ventilators communicates a pair of intercommunicating oppositely curved deflectors, inside the car communicating with one of the air intakes and disposed one below the other close to a side of the car. The top of the upper deflector projects within the ventilator and has its concave side towards that end of the car; and the lower deflector rests in the corner of the car beneath the ventilator with its concave side towards the body of the car and the upper and lower deflectors being arranged, as shown in Figure 2 with the upper in position to direct the downwardly deflected air into the curve of the lower deflector. The lower deflector projects the air into an air distributor in the form of a floor rack which extends from side to side of the car and the air being thus deflected from the bottom ends of the lower deflectors, at that end of the car, to the bottom ends of the deflectors at the opposite end of the car. In order to control the volume of air admitted the upper deflectors are preferably carried by sliding plates serving as valves controlling the air intakes. These valvular plates may be adjusted to vary the intake opening or cut it off entirely. Each end of the car has a screened

opening preferably located in the lower portion of each of the doors of the car and each is furnished with means for adjusting, or if desired completely closing these screened openings. The mouths of the air intakes are adapted to exclude dust from the air admitted by vertically disposed fine screens extending completely across the same.

An equipment in accordance with the foregoing causes pure air to permeate the entire interior of a car and while it rises through the body of the car near the front end where it is admitted nevertheless it will be drawn down again as it nears the outlets in the rear end of the car by the position of the outlets near the floor.

For full comprehension, however, of my invention reference must be had to the accompanying drawings in which similar reference characters indicate the same parts and wherein:

Figure 1 is an end view of a railway car constructed with my means for ventilating and deflecting the air admitted thereto, through the body of the car, this view indicating one half of the near end of the car in elevation and the other half of the opposite end of the car in elevation, the body of the car within the last mentioned half as illustrated, being in transverse sectional view;

Figure 2 is a side elevation of an end of a railway car partly broken away to illustrate the structure which ventilates and deflects; and

Figure 3 is a detail elevational section of the upper portion of the car shown in Figure 2.

In the drawings I have shown an express car with main deck 2 and upper deck 3, as an illustration of the application of the invention. It may be applied to any car, however, and in passenger cars the under sides of the usual seats whether used as seats or made up as berths, serve as distributors of the air projected beneath them by the deflectors.

Openings 4 are cut through the main deck 2 and extend in width from upper deck 3 to a point in line with the upper end of the side wall of the car as shown in Figure 1. Each of these openings has a ventilator A fitted therein and consisting of a hood presenting a flat top 5 with inwardly inclined back 6, Figure 2; the mouth of the ventilator having a screen 7 extending across it. screened mouth of the ventilator is located at one end of the opening 4. A pair of oppositely curved deflectors B and C are arranged one above the other, the upper end of the top deflector projecting within the ventilator, and is arranged with its concave side towards the end of the car while the lower deflector C rests in the corner of the car beneath the ventilator with its concave side towards the body 10 of the car and in communication with the concave side upper deflector. Both deflectors are preferably arranged in close proximity to a side of the car and the lower deflector is preferably of slightly greater width than the 15 upper deflector to facilitate the distribution of the air deflected thereto by the upper deflector. The openings 4 are closed by sliding valvular plates G upon one end of each of which is rigidly carried one of the upper 20 deflectors B so that by moving the sliding plates the ventilators may be partially or fully closed or opened. When the ventilator is closed in this manner the upper deflectors being carried by the plates will be placed in 25 contact with the end of the car and out of the way.

The air entering through the ventilators at the forward end of a moving car is deflected by the deflectors B and C and projected into a 30 flat air distributing member consisting of a floor rack D. This rack consists of a false flooring composed of narrow spaced boards 8 supported at their opposite ends on cross pieces 9 resting on posts 10. The spaces between these boards serve as slits through 35 which air may pass. This form of floor rack admits the air projected along the floor by the lower deflectors and the air thus admitted is distributed throughout the car through the 40 slits. In each end of the car the usual door 12 has its lower panel removed and the opening thus formed is covered by wire cloth E. This screened opening is controlled by a valvular panel 14 slideable vertically in guides 15. 45 When the car is put in motion the opening in the door at the forward end of the car is preferably closed and the opening in the rear door is regulated by its valvular panel in relation to the adjustment of the valvular plate 50 G controlling the air intake at the forward end of the car.

The device functions in either direction as follows:

The speed of the car forces a current of air 55 through the forward ventilators "A" in the roof and into the car where it is diverted by the deflectors "B" towards the forward end of the car and onto deflector "C." Deflectors C, because of their greater width, spread out 60 the air body and direct it into the space under the floor rack by which it is distributed

throughout the car from which it is exhausted through the rear ventilators "A" and end opening "E."

It is claimed that this system of air intake 65 and the arrangement of deflectors, coacting with the exhaust ventilators and end exhaust opening provides an efficient circulation of air in relation to the speed of train. The deflectors "B" being attached rigidly to the 70 sliding plates "G" which control the openings in roof ventilators "A" will be moved out of the way when the car is not being used in 75 ventilating service and all ventilating openings are closed.

What I do claim as my invention and which I regard as new and in which I claim an exclusive property and privilege and which I desire to secure by Letters Patent are:

1. In a railway car of the type described 80 the combination with an intake ventilator; of a pair of deflectors of curved form and located one above the other, the upper deflector being disposed with its concave side communicating with the air intake, and the lower deflector being disposed with its concave side 85 in communication with the upper deflector; a floor rack having the lower deflector communicating therewith, and an air outlet in the opposite end of the car.

2. In a railway car such as claimed in claim 1 wherein the intake ventilator communicates with an opening in the roof of the car; a slide for controlling the roof opening and having the upper deflector carried thereby.

3. In a railway car the combination with 90 a roof ventilator and a valvular plate for controlling the communication between the roof ventilator and the car; of means for directing the air from the ventilator towards the floor at the intake end of the car consisting of a pair of substantially vertically aligned curved deflectors, one being in communication with the roof ventilator with its concave side facing the end of the car, and the other deflector resting in the corner of the car beneath the roof ventilator with its concave side towards the body of the car, and in communication with the concave side of the upper deflector, and means extending parallel 100 to the floor of the car for distributing the air throughout the car, and a screened opening with means for controlling the same in the rear end of the car.

4. A railway car such as claimed in claim 115 3 and having the upper deflector carried by the valvular plate controlling the passage through the roof ventilator.

In testimony whereof I have signed my name to this specification.

ARCHIBALD STURROCK.
